CHARGE FORMING APPARATUS

Delphia H. Cleem, Pembina, N. Dak.

Application December 12, 1939, Serial No. 308,867
In Canada October 6, 1939

10 Claims. (Cl. 48—144)

This invention relates to a charge forming apparatus and has relation more particularly to an apparatus of this kind especially designed and adapted for use in connection with an internal combustion engine.

It is a particular object of the invention to provide an apparatus of this kind including a generator for vaporizing the liquid fuel before it is delivered to the venturi of the carburetor, together with means to allow free passage of air into the carburetor at all times when the motor is in operation resulting in higher compression and increased power.

It is also an object of the invention to provide a charge forming apparatus which permits the use of a low grade liquid fuel together with means operating to prevent the vapor generated from reverting back to liquid before reaching the cylinders of the motor.

Another particular object of the invention is to provide a charge forming apparatus which in its operation employs the heat from the exhaust and the suction of air to produce the proper mixture and wherein a free passage of air into the carburetor draws the vaporized fuel from a generator and delivers the same into the carburetor adjacent to and in advance of the venturi to be mixed with the valve regulated flow of air into the carburetor.

Furthermore, it is an object of the invention to provide an apparatus of this kind wherein the flow of liquid fuel into a generator is dependent upon the opening and closing movement of the butterfly valve within the intake manifold.

The invention consists in the details of construction and in the combination and arrangement of the several parts of my improved charge forming apparatus whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view partly in elevation and partly in section and somewhat diagrammatic in character illustrating a charge forming apparatus constructed in accordance with an embodiment of my invention;

Figure 2 is a detailed sectional view taken substantially on the line 2—2 of Figure 1;

Figure 3 is a fragmentary view taken longitudinally through the generator as herein disclosed;

Figure 4 is an enlarged fragmentary view in elevation of the means for regulating the flow of fuel into the generator under control of a butterfly within the intake manifold and more particularly the operating shaft for said butterfly;

Figure 5 is a detailed sectional view taken substantially on the line 5—5 of Figure 4;

Figure 6 is a fragmentary view partly in section and partly in elevation of the valve structure for regulating the air intake;

Figure 7 is an enlarged fragmentary view in section illustrating the free air delivery within the carburetor and the associated discharge for the vaporized fuel;

Figure 8 is a detailed sectional view taken substantially on the line 8—8 of Figure 6.

As disclosed in the accompanying drawings, 1 denotes a fuel riser for an intake manifold 8 having the usual connection with the cylinders of the motor. The lower end of the riser 1 is in communication with the top of an air chamber 2 having an air inlet pipe 3 in communication therewith through a side wall thereof. Operating in the pipe or conduit 3 in a conventional manner is a check valve 4 herein disclosed as of a butterfly type.

The riser 1 has therein a suitably positioned venturi 5 and within the riser 1 above the venturi 5 is a butterfly valve 6 mounted on and rotated by a rod 7. This rod 7 is to be operated in any desired manner.

Housing the intake manifold 8 into which the riser 1 opens is an exhaust manifold 9 and the central portion of this manifold 9 has a depending tubular outlet 10 which surrounds the riser 1 and extends downwardly along the riser 1 to the air chamber 2. The lower portion of the outlet 10 has extending substantially laterally therefrom a pipe 11 which is continued at its outer end by the exhaust line 12 terminating as desired but which is herein disclosed as having a portion substantially parallel to the outlet 10.

For a predetermined distance therealong the pipe 11 has a portion of its wall cut away to form an opening, as at 14, and said opening is normally closed by the cover section 15 which is detachably held in applied position, as indicated at 16. This opening 14 provides ready access to the interior of the pipe 11 particularly to facilitate the application or removal of the generator G. This generator G is preferably of a type similar to the generator as particularly described and claimed in my Patent #2,140,071 dated December 13, 1938.

This generator G, as is particularly illustrated in Figure 3, comprises a metallic tube 17 within which is disposed a metallic helix 18 preferably of steel which extends substantially the entire length of the tube 17. The coils of the helix 18 contact the wall of the tube 17 so as to conduct heat from this wall into the interior of the tube. Extending within and supported by the helix 18 in spaced relation with respect to the tube 17 is a perforated steel tube 19 open at both ends. The inlet end of the tube 19 is connected to a source of liquid fuel by the pipe 20. This pipe 20 extends outwardly thru the wall of the pipe 11 and leads to a needle valve casing 21, Figure 5. Leading from this casing 21 and in communication with a suitable source S of liquid fuel supply is a pipe line a. This pipe line a has interposed therein a sediment trap 22 provided with a conventional drain cap 23. This line a also has interposed therein a shut off valve 24 of any desired type and in advance of the trap 22 the line a has interposed therein a conventional type of float chamber 25. The pipe line a also has in communication therewith and preferably in advance of the float chamber 25 a tank 26 for gasoline or the like. The communication between the tank 26 and the line a is under control of the usual type of valve 27 while the discharge of the liquid fuel, such as kerosene or kindred low grade fuel, from the source of supply or tank S is controlled by a conventional valve 28 interposed in the line a at a point closely adjacent to the source or tank S.

As illustrated in Figure 1, the sediment trap 22 is carried by the bottom wall of the air chamber 2 thru the medium of an interposed bracket 29.

The valve casing 21 is provided with an internal seat 30 for the needle valve 31 threading into the casing 21 in the usual manner for coaction with the seat 30 to regulate or control the flow of the fuel through the line 20 of the generator G.

The portion of the needle valve 31 exteriorly of the casing 21 has fixed thereto a surrounding sleeve or collar 32. Outwardly of this collar 32 the valve 31 has freely mounted thereon the disks 33. Freely mounted on the needle valve 31 between the disks 33 is an end portion of a lever 34.

An expansible member 35 of desired tension is interposed between the outer disk 33 and the head 36 at the outer extremity of the valve 31. This member or spring 35 surrounds the needle valve 31 and serves to constantly exert pressure on the disks 33 and the interposed end portion of the lever 34 with the innermost disk 33 contacting the collar or sleeve 32. By this means the lever 34 is frictionally held or clutched to the needle valve 31 whereby rocking movement of the lever 34 will effect a rotation of the needle valve 31. However, by holding the lever 34 against swinging movement, the valve 31 may be readily turned through the medium of a head 36 to extend or retract the needle valve 31 with respect to its seat 30 in order to effect a selected regulation of the maximum flow of the fuel through the tube 20 to the generator G.

In the present embodiment of my invention the valve casing 21 is operatively supported by a bracket 37 extending outwardly from the leg 11. This bracket 37 has a lateral extension 38 underlying the needle valve 31. This extension 38 is provided with an outwardly and laterally directed lug 39 underlying the lever 34. Threaded from below through this lug 39 is an adjustable stop screw 40. This screw 40 is directly below

the lever 34 and is adapted to be contacted from above by the lever 34 to limit the extent of outward swinging movement of the lever 34 and the resultant outward movement of the needle valve 31.

The outer end portion of the lever 34 has operatively connected therewith an end portion of a rod 41, the opposite end of which is operatively connected, as at 42, with a rock arm 43 fixed to rotate with the operating shaft 7 for the butterfly 6. This rock arm 43 is held to the shaft 7 by the lock screw 44 whereby said rock arm 43 may be radially adjusted with respect to the shaft 7 as may be preferred. By varying the radial position of the lever 43 with respect to the shaft or stem 7 adjustment for low speed may be readily made.

The lever 34 is normally maintained at the limit of its outward movement as determined by the adjustment of the stop member 40 through the medium of the retractile spring 45 of required tension one end portion of which is secured, as at 46, to the rod 41 at a desired point intermediate its ends while the opposite end portion of the spring 45 is secured, as at 47, to the bracket 37 at a point inwardly of the casing 21.

The connection 42 between the rod 41 and the lever 43, as herein disclosed, specifically comprises a longitudinally disposed slot 48 in the end portion of the rod 41 immediately adjacent to the lever 43 and in which works a laterally disposed part or pin carried by the outer end portion of the lever 43. This slot 48 is of a length to allow the butterfly valve 6 to be adjusted from substantially half speed to full speed without exerting pull upon the rod 41, but when the butterfly valve is moved below half speed the lever 43 in its movement will have operative contact with the outer end of the slot 48 and exert pull upon the rod 41 to effect a closing movement of the needle valve 31. At this time it is to be particularly pointed out that it is important that the valve casing 21 be spaced not less than two inches from the exhaust pipe 11 so that the liquid fuel will not vaporize before the fuel enters the generator G by the heat radiating from the pipe 11.

The end of the tube 17 of the generator G opposite from the intake pipe 20 has leading therefrom a discharge pipe or tube 49 which enters the intake 1 through a vent tube 50 positioned below the venturi but discharging immediately adjacent thereto. The discharge end of the tube or pipe 49 is closely adjacent to the discharge end of the vent tube 50 and, as particularly illustrated in Figures 1 and 7, the vent tube 50 is of an internal diameter materially in excess of the major diameter of the portion of the tube or pipe 49 within said vent tube 50.

The vent tube 50 together with the associated discharge end portion of the pipe or line 49 is disposed on an upward inclination and the tube 50 is open at both ends. The inner open end of the tube 50 is in communication through a duct 51 with the air intake pipe or conduit 3 at a point closely adjacent to the point of communication of this pipe or conduit 3 with the air chamber 2. This duct 51, as herein disclosed, is formed through an outwardly enlarged portion 52 at the lower portion of the intake 1 and which enlarged portion is housed within the adjacent portions of the pipes 10 and 11 of the exhaust manifold whereby the air passing up through the duct 51 and into the intake 1 through the vent tube 50 is preheated.

It is to be particularly pointed out that the duct 51 together with the air vent 50 provide for a free passage of air into the manifold in advance of the venturi at all times when the motor is in operation.

The free air passing into the intake 1 through the vent tube or sleeve 50 draws the fuel into the generator G and takes the vaporized fuel from the generator G to the venturi 5 to be mixed with the proper amount of air entering the air chamber 2 through the pipe or conduit 3. It is also believed to be apparent that the heat from the exhaust in my improved apparatus heats the generator G and also maintains at even temperature the intake 1 so that the vaporized fuel as it passes through the intake will not condense or return to a liquid form.

The flow of the air into the air chamber 2 is under control of the valve member 53. This valve member 53 works within the air chamber 2 and is normally maintained closed under the action of a coil spring 54 of required tension interposed between the valve member 53 and the inner end of a regulating member 55. This member 55 is provided at the axial center of its inserted end with an elongated supporting rod 56 which freely passes through an opening 57 positioned at the axial center of the valve member 53. This rod 56 serves as a support or mounting for the valve member 53.

The adjusting member 55 threads through a side wall of the air chamber 2 and is provided at its outer or extended extremity with an operating head 58 whereby the tension of the spring 54 may be regulated or adjusted as required. The member 55 is maintained in its selected adjusted position through a conventional lock nut 59.

In starting the motor the gasoline within the tank 26 is used with of course the valve 28 closed and the low grade fuel within the pipe line a being previously drained out. After the generator G becomes hot the valve 27 is closed to shut off the flow of gasoline, the valve 28 opened whereupon the motor will continue to run on the charge produced from the low grade fuel.

The portion 60 of the wall of the air intake pipe or conduit 3 through which the duct 51 is directed is of increased thickness to allow a screw 61 to protrude more or less into the duct 51, it being manifest that the farther the screw is moved into this duct the less amount of air will be taken in and that the amount of air may be increased at will when the screw is moved outwardly. The screw is shown as provided with a knurled finger piece 62 and a nut 63 to hold the screw in its desired adjusted position. It is also to be noted that the tube 50 adjacent to its discharge end has therein a Venturi sleeve 64 in order to give more suction on the tube or pipe 49.

The present application is partly in continuation of my application Serial No. 286,935 filed July 27, 1939 and embodies the added features pertaining to the screw 61 and the Venturi sleeve or tube 64.

From the foregoing description it is thought to be obvious that a charge forming apparatus constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and forma-

tion of the several parts herein shown in carrying out my invention in practice except as hereinafter claimed.

I claim:

5. 1. A charge forming apparatus for an internal combustion engine comprising, in combination, an intake delivering to the cylinders of the motor, said intake having a venturi therein, a valve controlled air passage in communication with the intake below the venturi, means in communication with the intake closely adjacent to the narrow part of the venturi for the free admission of air to the intake, means for delivering air free fuel to the intake adjacent the said admission means, and means for vaporizing the fuel passing through the fuel delivering means.
10. 2. A charge forming apparatus for an internal combustion engine comprising, in combination, an intake delivering to the cylinders of the motor, said intake having a venturi therein, a valve controlled air passage in communication with the intake below the venturi, a free air passageway venting at one end into said intake adjacent to the narrow part of the venturi, a fuel delivery line discharging at one end in the venting end of the free air passageway and into the intake and means for vaporizing the fuel in and passing through the fuel line.
15. 3. A charge forming apparatus for an internal combustion motor comprising, in combination, an intake delivering to the cylinders of the motor, said intake having a venturi therein, an air passage in communication with the intake below the venturi, a suction opened valve controlling said air passage, means in communication with the intake closely adjacent to and between the narrow part of the venturi and said valve for the free admission of air to the intake, means for delivering fuel free of air to the intake adjacent the discharge end of said free air admission means, and means for vaporizing the fuel before the fuel is delivered into the intake.
20. 4. A charge forming apparatus for an internal combustion motor comprising, in combination, an intake delivering to the cylinders of the motor, said intake having a venturi therein, an air passage in communication with the intake below the venturi, a suction opened valve controlling said air passage, a free air passage having a discharge end in communication with the intake closely adjacent to and between the narrow part of the venturi and said valve for the free admission of air to the intake, means for delivering air free fuel into the intake closely adjacent to the discharge end of said free air admission means, and means for heating the air as it travels through the said free air passage.
25. 5. A charge forming apparatus comprising an intake delivering to a fuel consuming device, said intake having a venturi therein, a valve controlled air passage leading into the intake below the venturi, a free air passage having one end opening into the intake within the venturi, a venturi in the said free air passageway adjacent the said one end of the free air passageway, and a fuel delivery line opening into the second mentioned venturi adjacent the narrow part thereof for discharge of fuel free of air into and through the second mentioned venturi to flow from the said end of the free air passageway into the narrow part of the first mentioned venturi and into the intake.
30. 6. A charge forming apparatus for an internal combustion engine, comprising an intake pipe communicating at one end with the cylinders

of the engine, a venturi in said pipe, the other end of the pipe receiving fuel-free air, a tube extending obliquely into the pipe and terminating at the axial center thereof and opening into the venturi adjacent the narrower part thereof, means for delivering fuel-free air to said tube, a venturi in the tube adjacent the end opening into the venturi of the intake pipe, and means for delivering fuel into the venturi of the tube for admixture with air entering the intake pipe by way of the tube.

7. A charge forming apparatus as set forth in claim 6, including two valves controlling the admission of air to the intake pipe, the said air delivering means for said tube leading off from said pipe at a point between the two valves, and that one of the two valves nearest to the first venturi being constructed and arranged to open in response to a predetermined pressure reduction in the intake pipe upon the venturi side of the said one valve.

8. A charge forming device comprising an intake for a fuel consuming device, a butterfly valve mounted therein, an operating shaft therefor, a fuel line delivering within the intake, a valve mechanism including a valve member for controlling the flow through said fuel line, said valve member being of a needle type, a rock arm loosely mounted on the valve member to permit the valve member to be adjusted independently of the rock arm, means for releasably locking the rock arm to the valve member to permit said valve member and rock arm to move in unison, and an operative connection between the shaft of the butterfly valve and said rock arm for swinging said rock arm upon turning movement of the shaft of the butterfly valve.

9. A charge forming device comprising an intake for a fuel consuming device, a butterfly valve mounted therein, an operating shaft therefor, a fuel line delivering within the intake, a valve mechanism including a valve member for controlling the flow through said fuel line, said valve member being of a needle type, a rock arm loosely mounted on the valve member to permit the valve member to be adjusted independently of the rock arm, means for releasably locking the rock arm to the valve member to permit said valve member and rock arm to move in unison, an operative connection between the shaft of the butterfly valve and said rock arm for swinging said rock arm upon turning movement of the shaft of the butterfly valve, and means for limiting the movement of the rock arm in one direction.

10. A charge forming device comprising an intake for a fuel consuming device, a butterfly valve mounted therein, an operating shaft therefor, a fuel line delivering within the intake, a valve mechanism including a valve member for controlling the flow through said fuel line, said valve member being of a needle type, a rock arm loosely mounted on the valve member to permit the valve member to be adjusted independently of the rock arm, means for releasably locking the rock arm to the valve member to permit said valve member and rock arm to move in unison, an operative connection between the shaft of the butterfly valve and said rock arm for swinging said rock arm upon turning movement of the shaft of the butterfly valve, means for limiting the movement of the rock arm in one direction, and means for normally maintaining said rock arm at such limit of its movement.

DELPHIA H. CLEEM.
